UNITED STATES PATENT OFFICE.

SAMUEL COOMBS, OF KENNINGTON ROAD, COUNTY OF SURREY, ENGLAND.

DOOR-CHECK.

SPECIFICATION forming part of Letters Patent No. 349,384, dated September 21, 1886.

Application filed March 4, 1886. Serial No. 193,922. (No model.)

To all whom it may concern:

Be it known that I, SAMUEL COOMBS, a subject of the Queen of Great Britain, and residing at 11 Wincott Street, Kennington Road, 5 in the county of Surrey, and Kingdom of Great Britain, joiner, have invented a certain new and useful Mechanical Door-Check; and I do hereby declare that the following is a full, clear, and exact description of the invention, which will enable others skilled in the art to which it appertains to make and use the same.

The mechanical door - check forming the subject of this invention is intended to prevent doors from slamming when they are closing. It may be used with any door-closing spring, or with spring-hinges, and it may be fixed either in the hanging - stile of the door or in the corresponding post of the door-frame. 15 The construction of the check is illustrated in the drawings hereto annexed, in which Figure 1 is a sectional elevation, and Fig. 2 a sectional plan, showing the check as applied to the hanging-post of a door.

20 A and B are two strong metal levers or arms, fitted inside a strong metal case, D, inserted and secured in a mortise in the hanging-post J of the door-frame. The fulcra of these levers are at I and H, respectively. A 25 knob or projection, F, is fixed to or formed with the lever A, and passes through a hole in the face-plate E of the case D. The lever B is acted on by a spring, G, which tends constantly to force the free end of the lever B in 30 the direction of the arrow against the stop K.

The levers A and B are placed so as to form an angle with each other, the inner edges forming two inclined planes, between which is placed a sliding piece, C, preferably of 35 hard wood, or of metal or other suitable material.

When the door L closes, the edge of the hanging-stile, or, preferably, a metal plate, M, secured therein, comes against the knob or projection F, as shown in Fig. 2. The upper end of the lever A is thereby pushed inward, pressing against the sliding piece C, which reacts upon the lever B, the immediate effect being to turn the said lever B slightly on its

center H against the action of the spring G, 50 so as to avoid any sudden rebound of the door; but when the sudden closing force of the door is expended the spring G restores the lever B to its normal position against the stop K. In consequence of the angular position of the levers A and B with regard to each other, and the correspondingly-tapered or wedge form of the piece C, the movement of the lever A on its fulcrum I causes the piece C to slide upward between the two levers, but with a certain amount of friction, which acts as a brake or resistance that retards the closing of the door. The piece C continues to slide upward until the door is completely closed by the action of its closing- 55 spring or spring-hinges. When the door is opened again, the lever A and the piece C return by their own weight into the positions shown in Fig. 1, ready to act again in the same way.

Figs. 3 and 4 show a modification of the above-described arrangement, in which the piece B is fixed in the case D, and does not turn on a fulcrum like the piece B in Figs. 1 and 2, the shock of closing being in this case 75 wholly absorbed by the friction of the sliding piece C in sliding up between the lever A on the one hand and the fixed piece or abutment B on the other. The spring G of Fig. 1 is of course not required in this case.

N is a piece of leather or other soft material fixed to the piece C, and bearing lightly against the edges of the pieces A and B, for the purpose of keeping the said edges free from dirt as the said sliding piece moves up and 85 down between them.

Similar letters of reference relate to like parts in all the figures of the drawings.

If preferred, the case D with its contents may be secured in the hanging - stile of the 90 door, instead of in the door-post, as shown in the drawings, and in that case the knob or projection F will come in contact with the door - post as the door closes, and the action and effect of the parts will be the same as above 95 described.

In some cases I combine my door-check with a hinge (either a spring-hinge or otherwise)

in such manner that the face-plate E forms one of the leaves of such hinge.

I claim—

A mechanical door-check constructed with 5 the parts A and B placed at an angle with each other, in combination with the frictional taper or wedge-shaped sliding piece C, arranged between them, the part A being acted

on by the edge of the door or door-frame, substantially as described and illustrated.

SAMUEL COOMBS.
